(57) **CLAIM**

The ornamental design for a display screen or a portion thereof with graphical user interface, as shown and described.

DESCRIPTION

FIG. 1 is a view of a display screen or a portion thereof with graphical user interface; and,

FIG. 2 is a view of a second embodiment thereof. The outer broken line represents a display screen or a portion thereof and forms no part of the claimed design.

1 Claim, 2 Drawing Sheets

FIG. 1

FIG. 2
